(57) **CLAIM**

The ornamental design for an electrosurgical device handle, as shown and described.

DESCRIPTION

FIG. 1 is a front perspective view of an electrosurgical device handle, showing our new design;

FIG. 2 is a rear perspective view of the electrosurgical device handle of FIG. 1 in an inverted position;

FIG. 3 is a top side view of the electrosurgical device handle of FIG. 1;

FIG. 4 is a bottom side view of the electrosurgical device handle of FIG. 1;

FIG. 5 is a left side view of the electrosurgical device handle of FIG. 1;

FIG. 6 is a right side view of the electrosurgical device handle of FIG. 1 in an inverted position;

FIG. 7 is a front side view of the electrosurgical device handle of FIG. 1; and,

FIG. 8 is a rear side view of the electrosurgical device handle of FIG. 1.

The broken lines shown in FIG. 8 represent portions of the electrosurgical device handle that form no part of the claimed design.
